UNITED STATES PATENT OFFICE.

WILLIAM HATTON STEVENS, OF HOLLIDAYSBURG, PENNSYLVANIA.

TOOL HANDLE.

Application filed October 18, 1922. Serial No. 595,442.

The handle of my invention is adapted for shovels, spades, forks and the like, and it is designed to provide an improved construction at reduced cost.

5 The handle is characterized, in its preferred form, by the combination of a wood stem with a D-top or hand piece having its base, clevis and grip formed of an integral homogeneous block of hardened plastic vegetable material molded around the handhole and containing a socket for the stem or shaft.

A preferred form of my D-handle is set out in the following description and the accompanying illustration thereof.

In the illustrations, Fig. 1 is an elevation representing both the front and back view of the top of a handle embodying a preferred form of my invention, Fig. 2 is a sectional view taken on the line 2^x—2^x of Fig. 1, and Fig. 3 is a sectional view taken on the line 3^x—3^x of Fig. 1.

20 The handle illustrated comprises the wood stem or shaft 1 having the reduced top 2 to provide a species of tenon for engagement in the D-hand piece 3 to be fixed to the stem or shaft.

The hand piece 3 is composed of an integral homogeneous block of hardened plastic vegetable material molded around the handhold 3^a to form the base 3^a clevis 3^b, and grip 3^c. The metal bushing 4 is set in the base 3^a

and the part 2 is set in this bushing, the bottom of the part 3 and of the part 4 abutting against the shoulder 5 of the stem. A bolt 35 or rivet 6 passes through the parts 2, 3 and 4 transversely to the parts 2 and 4 and parallel to the front and back of the part 3.

The part 3 can be made of various fibrous materials mixed with various binders, as 40 kelp pulp, sawdust or ground leather mixed with casein or plaster bakelite, suitably in equal parts thoroughly mixed, molded and the molded form baked.

This handle is strong, durable and inexpensive, avoiding the waste involved in all-wood D-handles.

In this form of my invention, which differs specifically from that of my patent No. 1,565,599, the handle can be produced at 50 lower cost with some sacrifice in the strength which characterizes the handle of such patent, but with the provision of a handle that is generally satisfactory.

Having described my invention, I claim: 55
A tool handle comprising a D-hand piece having its base, clevis and grip formed of an integral homogeneous block of hardened plastic vegetable material molded around a handhold and containing a socket for a shaft. 60

Signed at Altoona, in the county of Blair and State of Pennsylvania, this 16th day of October, 1922.

WILLIAM HATTON STEVENS.
